UNITED STATES PATENT OFFICE.

JOHN J. BECKER, OF LOS ANGELES, CALIFORNIA.

PUMPING MACHINERY.

1,202,151.

Specification of Letters Patent. Patented Oct. 24, 1916.

Application filed June 5, 1915. Serial No. 32,333.

To all whom it may concern:

Be it known that I, JOHN J. BECKER, a citizen of the United States, residing at Los Angeles, in the county of Los Angeles and 5 State of California, have invented new and useful Improvements in Pumping Machinery, of which the following is a specification.

My invention relates to novel and improved pumping machinery and in particular to a mechanism for operating a double acting plunger pump.

It is an object of this invention to construct an apparatus whereby the walking beams each carrying a floating gear eccentrically mounted intermediate its ends, are vertically reciprocated. The forward ends of the outer beams are connected together by means of a yoke which operates the outer 20 plunger rod while the intermediate beam is connected at its forward end to the inner plunger rod. The rear ends of said beams are provided with sectional gears which are kept in mesh with a stationary gear, the 25 curvature of the sectional gears being designed in such a way that the forward ends of said beams are caused to vertically reciprocate in straight lines.

Another object of this invention is to provide a series of eccentrically mounted gears actuating the beams whereby a simple and efficient construction, positive in its operation, is provided, and the power is evenly distributed, avoiding jars and stresses in the 35 various parts of the apparatus.

These and other objects of the invention will appear as the description proceeds and will be pointed out in the appended claims.

In the accompanying drawings which 40 form a part of this specification I have shown a convenient and practical embodiment of the apparatus and in which:

Figure 1 is a side elevation with parts broken away of the apparatus. Fig. 2 is a 45 top plan view thereof. Fig. 3 is a front elevation with parts broken away, showing the connection of the plunger rods.

Like reference numerals indicate like 50 parts throughout the several views of the drawings.

In a frame 10, composed of two sections and suitably connected with tie rod 11 and cross bar 12 at the forward upper end of the apparatus, a driving shaft 14 is suitably 55 journaled. Power from any source is transmitted to pulley 15 fast to one end of said

shaft. A driving gear pinion 16 secured to the other end of said shaft, drives a large gear 17 fast to the countershaft 18 suitably journaled in frame 10. Secured to shaft 18 are gear wheels 19, 20 and 21, equi-distantly spaced from each other. Gears 19 and 21 operate the outer walking beams A and A' while gear 20 operates the intermediate walking beam B. The walking beams A and A' move in unison and carry on their forward ends in pivotal engagement, vertical rods 22 and 22', respectively, which at their lower ends are connected by means of a yoke 23, to which is secured the outer plunger rod 24. The intermediate walking beam B carries at its forward end in pivotal engagement vertical rod 25 which is connected to the inner plunger rod 26, the latter working within the outer plunger rod 24, as is usual in double acting plunger pumps. The gears operating the walking beams are arranged in such a manner that the outer beams A and A' will move in opposite direction to walking beam B so that when the upper limit of movement of beam B is reached, beams A and A' will occupy the lowest position, as shown in Fig. 1, and as will be readily understood.

The arrangement and position of the 85 gears operating A and A' are exactly alike and it will therefore only be necessary to describe the gears operating the beam A'. Assuming that the walking beams are in the position shown in Fig. 1, it will be seen 90 that the lower eccentric gear 21 fast on shaft 18 meshes with intermediate eccentric gear 27 in such a way that when walking beam A' occupies its lowest position their centers of rotation will lie closest together. Gear 95 27 is loosely mounted on a pin or rod 28 passing transversely through beam A'. A slot 29 is cut longitudinally through said beam of a size sufficiently large to allow gear 27 to revolve therein. The upper part of gear 27 meshes with an upper gear 35 which is loosely mounted on stationary rod 36 transversely secured in the upper part of the frame. Gear 35 is eccentrically mounted on rod 36 and when beam A' is in the 100 lowest position, as shown in Fig. 1, the top part of the gear is nearest to rod 36 or, in other words, rod 36 and rod 28 have reached the maximum distance of separation from each other.

Referring now to the gears of beam B, the lower eccentric gear 20 secured to shaft 18

drives intermediate eccentric gear 37 loosely mounted on pin 38 passing transversely through a longitudinal slot in beam B. Gear 37 in turn meshes with upper eccentric gear 39 loosely mounted on rod 36. The size of the gears, their position and eccentricity relative to their respective shafts are exactly the same as those described in connection with beams A and A'. Their position, 10 however, in relation to the gears described in connection with beam A' is exactly the opposite, that is to say when the upper part of lower gear 21 is nearest to shaft 18, as shown in Fig. 1, the upper part of lower gear 20 will be farthest away from said shaft causing beam B to occupy its highest position, the distance between shaft 18 and pin 38 being the maximum separation. The upper part of upper gear 39 will be farthest 20 away from rod 36.

Transversely secured to the upper part of the rear frame is a stationary rack 40. The teeth of rack 40 are adapted to engage with a segmental gear 41 formed on the rear 25 ends of beams A, A' and B. The forward ends of the beams will describe a rectilinear movement and will cause a corresponding vertical rectilinear movement of the pins carried by the beams on which the intermediate eccentric gears are loosely mounted. It will be obvious from the construction of the stationary rack 40 and the segmental gear 41 that the forward end of each beam 30 will describe a straight line while moving in the intermediate portion of its path. This intermediate portion corresponds to approximately the length of the stationary rack 40. The structure of Fig. 1 shows a stationary rack which is materially smaller in length 35 than the length of the movement of the forward ends of the walking beams, and consequently the extreme ends of the path of the movement will tend to turn slightly inwardly toward the gears. However, the ends 40 of said walking beams are maintained in vertical straight lines, because of the lost motion between the teeth of the stationary rack and the segmental gear. It is preferable however, as will be understood, to have the 45 length of the stationary rack correspond to the length of the movement of the outer ends of the walking beams, so that the latter may be rigidly maintained in rectilinear paths.

In order to insure positive engagement of 50 segmental gear 41 and rack 40 I have provided the following mechanism: A segment of a ring 42 is secured to the outer ends of segmental gear 41 which encircles rack 40. At a point approximately the center of the 55 ring an enlargement 43 is made providing a slot in which a roller 44 is rotatably mounted on a pin passing transversely through said slot. This roller engages a cam 45 formed in the rear of rack 40. The 60 cam is shaped in such a way that when the

segmental gear 41 engages rack 40 in its rocking movement, and ring 42 is oscillated, the roller 44 engaging cam 45 will insure positive engagement of said rack 40 and gear 41. In order to prevent lateral movement of the segmental gear a pair of ears 65 70 46 extending on opposite sides of enlargement 43 and engaging cam 45, are provided. The forward ends of the beams are slotted and carry therein, spaced a slight distance 75 from the end thereof, an antifriction roller 47 loosely mounted on a pin passing transversely through said slotted ends. The extreme slotted ends and antifriction roller 47 engage vertical uprights 49. The slotted 80 ends engage said uprights at opposite sides thereof and prevent any lateral movement of the forward ends of the beams. The anti-friction rollers, as well as the uprights 49, may be dispensed with since the mechanism 85 provided at the rear end of the beams for insuring positive engagement of the gear 41 and rack 40 will cause vertical reciprocatory movement of the forward ends of the beams without any assistance on the part of the 90 uprights 49.

The operation of the pumping apparatus will be easily understood from the foregoing description. Power applied to pulley 15 in a clockwise direction will, through the 95 transmission of gears 16 and 17, cause counterclockwise rotation of shaft 18. The revolution of eccentric gears 19 and 21 to the intermediate floating gears mounted in said beams will cause the latter to vertically 100 reciprocate the outer beams in unison and in opposite direction from the intermediate beam so that when the outer gears occupy the lowest position the intermediate beam will occupy its highest position and vice 105 versa. It should be noted that the gears mounted on rod 36 are not necessary for the reciprocation of the beams, in other words, the beams would operate if the upper 110 gears mounted on shaft 36 were absent. The purpose of the upper gears is to cause a positive downward movement of the beams if, for any reason, the plunger rods should meet with an obstruction. In such a case, if it were not for the upper gears 115 mounted on rod 36, the beams would stay in their upper positions and the intermediate floating gears would get out of mesh with the lower gears mounted on shaft 18. It is therefore seen that the upper gears 120 cause a positive engagement between the three gears for each beam.

By my improved pumping apparatus I distribute the strains and stresses usually found in pumping machinery. The balanced arrangement of the coating parts and the eccentric gears eliminate disadvantages present when a crank is used for reciprocating the walking beams.

Other advantages will be obvious to those 130

skilled in the art. It is to be understood that various changes may be made without departing from the spirit of my invention and from the scope of the appended claims.

5 I claim:

1. In an apparatus for operating double acting plunger pumps, a frame, a shaft journaled therein, means to rotate the same, an intermediate walking beam, a pair of outer walking beams arranged at opposite sides thereof, a vertical rod pivotally secured to the forward end of said intermediate beam and connected to an inner plunger rod, a pair of rods pivotally connected to said outer beams, a yoke connecting the same, a rod secured to said yoke and connected to the outer plunger rod, an intermediate lower eccentric gear secured to said shaft, an intermediate eccentric floating gear mounted on said intermediate beam in mesh with said lower gear, an upper eccentric gear, a rod secured to the upper part of said frame on which said upper gear is loosely mounted, said upper gear being in mesh with said intermediate gear, a pair of lower eccentric gears secured to said shaft on opposite sides of the first named lower gear, a pair of intermediate eccentric floating gears secured to said outer beams and in mesh with said outer lower gears, a pair of upper eccentric gears loosely mounted on said upper rod in mesh with said outer intermediate gears, whereby the outer ends of said beams are vertically reciprocated and when said intermediate beam is in its highest position the centers of revolution of the lower intermediate gears operating the same are farthest apart and when said beam is in its lowest position the centers of rotation of the upper intermediate gears are farthest apart and the outer beams will move in opposite direction to that of the intermediate beam, a stationary vertical rack having a cam face on the opposite side, a segmental gear at the rear end of each of said beams engaging said rack, a segmental ring secured to the ends of said segmental gears encircling said rack, a cam engaging roller carried by said ring, and cam engaging means on said ring for preventing lateral movement of said segmental gears.
2. In an apparatus for operating double acting plunger pumps, a frame, a shaft journaled therein, means to rotate the same, an intermediate walking beam, a pair of outer walking beams arranged at opposite sides thereof, plunger rod connections pivotled to the forward ends of said beams, intermediate eccentric gears rotatably mounted on said beams at a point intermediate the ends thereof, a plurality of lower eccentric gears secured to said shaft, a rod transversely mounted in the upper part of said frame, a plurality of upper eccentric gears rotatably mounted on said rod, said

intermediate gears being in meshing engagement with said lower and said upper gears, the position of the centers of revolution of said gears being so arranged that said intermediate beam and said pair of outer beams vertically reciprocate in opposite directions, a stationary vertical rack, a cam integral therewith on the opposite side thereof, a segmental gear at the rear end of each of said beams engaging said rack, a segmental ring secured to the ends of said segmental gear encircling said rack, a cam engaging roller mounted on said ring, means on said ring for preventing lateral movement of said segmental gear, and means mounted on the front end of the frame for preventing lateral movement of the front ends of said beams.

3. In an apparatus for operating double acting plunger pumps, a frame, a shaft journaled therein, means to rotate the same, an intermediate walking beam, a pair of outer walking beams arranged at opposite sides thereof, plunger rod connections pivotled to the forward ends of said beams, intermediate eccentric gears rotatably mounted on said beams, a plurality of lower eccentric gears secured to said shaft, a rod transversely mounted in the upper part of said frame, a plurality of upper eccentric gears rotatably mounted on said rod, said intermediate gears being in meshing engagement with said lower and said upper gears, the position of the centers of revolution of said gears being so arranged that said intermediate beam and said pair of outer beams vertically reciprocate in opposite directions, a stationary gear, a cam integral therewith, a segmental gear at the rear end of each of said beams engaging said stationary gear, a cam engaging roller connected to said segmental gear, means for preventing lateral movement of said segmental gear, and means for preventing lateral movement of the front ends of said beams.

4. In an apparatus for operating double acting plunger pumps, a frame, a rotating shaft journaled therein, an intermediate walking beam, a pair of outer walking beams arranged at opposite sides thereof, a train of eccentric gears actuated by said shaft for vertically reciprocating said beams, the position of the centers of revolution of said gears being so arranged that said intermediate beam and said pair of outer beams move in opposite directions, a stationary gear, a segmental gear at the rear end of each of said beams engaging said stationary gear, means connected to said beams for holding said stationary gear and said segmental gear in positive engagement with each other, and means for preventing lateral movement of said beams.

5. In an apparatus for operating double

- acting plunger pumps, a frame, a rotating shaft journaled therein, an intermediate walking beam, a pair of outer walking beams arranged at opposite sides thereof, 5 plunger rod connections pivoted to the forward ends of said beams, a train of eccentric gears operated by said shaft, one of said gears being rotatably mounted in each of said beams, the position of the centers of 10 revolution of said gears being so arranged that said intermediate beam and said pair of outer beams vertically reciprocate in opposite directions, a stationary gear, a segmental gear at the rear end of each of said 15 beams engaging said stationary gear, means for holding said stationary gear and said segmental gear in positive engagement, and means for preventing lateral movement of the front ends of said beams.
- 20 6. In an apparatus for operating double acting plunger pumps, a frame, a rotating shaft journaled therein, an intermediate walking beam, a pair of outer walking beams arranged at opposite sides thereof, 25 plunger rod connections pivoted to the forward ends of said beams, a train of eccentric gears operated by said shaft, one of said gears being rotatably mounted in each of said beams, the position of the centers of 30 revolution of said gears being so arranged that said intermediate beam and said pair of outer beams vertically reciprocate in opposite directions, a stationary gear, and a segmental gear at the rear end of each of said 35 beams, engaging said stationary gear.
7. In an apparatus for operating double acting plunger pumps, a frame, a rotating shaft journaled in said frame, a pair of outer walking beams, an intermediate walking beam between the beams of said pair of outer walking beams, gears eccentrically secured on said shaft, gears eccentrically journaled on said walking beams and meshing with the gears on said shaft, the position of 40 the centers of revolution of said gears being such that said intermediate beam and said pair of outer beams will move in opposite directions upon rotation of said shaft, a rack, a segmental gear at the rear end of 45 each of said beams engaging said rack, means connected to said beams for holding said rack and said segmental gear in positive engagement with each other and means for preventing lateral movement of said 50 beams.
8. In an apparatus for operating double acting plunger pumps, a frame, a shaft journaled therein, means to rotate the shaft, an intermediate walking beam, a pair of outer walking beams arranged at opposite sides of said intermediate walking beam, a vertical rod pivotally secured to the forward end of said intermediate beam and connected to an inner plunger rod, a pair of rods pivotally connected to said outer beams, 55 a cross yoke connecting the same, a rod secured to said yoke and connected to the outer plunger rod, an intermediate lower eccentric gear secured to said shaft, an intermediate eccentric floating gear mounted on said intermediate beam in mesh with said lower gear, a pair of lower eccentric gears secured to said shaft on opposite sides of the first named lower gear, a pair of eccentric floating gears secured to said outer beams and in mesh with said outer lower gears whereby the outer ends of said beams are vertically reciprocated and when said intermediate beam is in its highest position, the centers of revolution of the gears operating the same are farthest apart and when said beam is in its lower position, the centers of rotation of the outer gears are farthest apart and the outer beams will move in opposite direction to that of the intermediate beam, a stationary vertical rack having a cam face on the opposite side, a segmental gear at the rear end of each of said beams engaging said rack, a retaining yoke secured to the ends of said segmental gears encircling said rack, a cam engaging roller carried by said yoke and cam engaging means on said yoke for preventing lateral movement of said segmental gears. 70 75 80 85 90 95 100 105 110 115 120 125 130
9. In an apparatus for operating double acting plunger pumps, a frame, a shaft journaled therein, means to rotate the shaft, an intermediate walking beam, a pair of outer walking beams arranged at opposite sides thereof, plunger rod connections pivoted to the forward ends of said beams, eccentric gears rotatably mounted on said beams, a plurality of lower eccentric gears secured to said shaft, said first named gears being in meshing engagement with said lower gears, the position of the centers of revolution of said gears being so arranged that said intermediate beam and said pair of outer beams vertically reciprocate in opposite directions, a stationary gear, a cam integral therewith, a segmental gear at the rear end of each of said beams engaging said stationary gear, a cam engaging roller connected to said segmental gear and means for preventing lateral movement of said segmental gear. 120 125 130
10. In an apparatus for operating double acting plunger pumps, a frame, a shaft journaled therein, means to rotate the same, an intermediate walking beam, a pair of outer walking beams arranged at opposite sides thereof, plunger rod connections pivoted to the forward ends of said beams, eccentric gears rotatably mounted on said beams at a point intermediate the ends thereof, a plurality of lower eccentric gears secured to said shaft, said first named gears being in meshing engagement with said lower gears, the position of the centers of revolution of said gears being so arranged that said intermediate beam and said pair of outer beams 130

vertically reciprocate in opposite directions, a stationary vertical rack, a cam integral therewith, a segmental gear at the rear end of each of said beams engaging said rack, a retaining yoke secured to the ends of said segmental gear encircling said rack, a cam engaging roller mounted on said yoke, means

on said yoke for preventing lateral movement of said segmental gear, and means for keeping the gears in mesh and returning the 10 beams.

In testimony whereof I have signed my name to this specification.

JOHN J. BECKER.
